UNITED STATES PATENT OFFICE

ALBERT F. STUEBING, OF NEW YORK, N. Y., ASSIGNOR TO THE BRADFORD PATENTS CORPORATION, OF NEW YORK, N. Y., A CORPORATION OF DELAWARE

FRICITION DRAFT GEAR

Application filed January 25, 1926. Serial No. 83,698.

My invention relates to friction draft gears employed in connecting railway cars and particularly to such a gear which includes two groups of friction plates movable longitudinally and respectively in response to pulling and pushing strains, the plates of each group being alternated with the plates of the other group, that is, the plates being in so-called intercalated arrangement.

The invention has a number of advantageous characteristics among which are the provision of a spreading device, preferably a wedging device, which is subject to draft strains and is disposed in the midst of the plates of both groups and which presses outwardly upon the plates on each side thereof in response to draft strains, and a constricting device, also preferably a wedging device, operating in conjunction with the spreading device, and also subject to and operable by draft strains and laterally embracing both groups of plates and pressing inwardly upon the plates in response to draft strains; application springs, located abreast, and a spacer, preferably a floating draft strain transmitting member interposed between these springs and the constricting device and through which member said springs operate upon said constricting device to cause it to press inwardly upon the plates; release springs operating upon one group of plates to effect relatively releasing movement of said groups of plates upon reduction in draft strain, a spacer between the springs, and a spanner crossing the spacer and interposed between the release springs and the group of plates affected thereby; the provision of strengthening formations upon portions of some of the plates that are projected beyond the paths of movement of plates contiguous thereto, such strengthening formations being desirably afforded by thickening or crowning the plates thus projected; a center column serving as a spacer between the two release springs which desirably enclose the application springs and operating to limit the maximum extent of relative movement of the two groups of plates in response to draft strains, this center column having a portion

which constitutes or is included in the construction of the spreading device, this portion of the center column being itself desirably wedge shaped, though the invention is not to be thus restricted; the employment of a floating member between the application springs and the constricting device and extending across the center column that extends longitudinally of the gear on both sides of this floating member; an arrangement of the plates of both groups in similar directions oblique to the axis of the gear to produce motion retarding friction as the two groups of plates are moved longitudinally of the gear in response to draft strains; the provision of constricting mechanism resisting the transverse movements of the obliquely arranged plates in response to draft strains; the provision of application spring mechanism for transmitting draft strains to the constricting mechanism whereby the resisting action of the constricting mechanism increases and is augmented by frictional resistance as the draft strain increases; the employment of wedging blocks through which said application spring mechanism functions; and the arrangement of the center column to withstand oversolid impact to protect the gear.

The invention has other useful features that will be more fully described in connection with the accompanying drawings in which Fig. 1 is a plan view of a friction draft gear constructed in accordance with the preferred embodiment of the invention, parts being shown in section, this figure being taken generally on line 1—1 of Fig. 2; Fig. 2 is a sectional elevation on line 2—2 of Fig. 1; Fig. 3 is a side view of part of the gear, partially in section, showing other features of construction not illustrated in Fig. 2; Fig. 4 is a plan view of part of the gear, with parts shown in section, showing parts not illustrated in Fig. 1; Fig. 5 is a sectional view on line 5—5 of Fig. 1; Fig. 6 is a sectional view on line 6—6 of Fig. 1; Fig. 7 is a perspective view illustrating the center column and the floating member that is in actuating relation to the constricting device, these

parts being shown in separated relation; Fig. 8 is a perspective view of the spanner which crosses the center column and is interposed between the release springs and the 5 plates; Fig. 9 is a perspective view illustrating one friction plate of each of the two groups of plates; and Fig. 10 is a perspective view showing the parts of the constricting device in separated relation.

10 The draft gear of my invention may include any suitable form of coupler and yoke and may be associated with any suitable form of draft sills.

15 The coupler stem 1, illustrated in the drawings, is provided with a key 2 extending transversely therethrough and snugly fitting the same to travel therewith. I have illustrated a yoke which is inclusive of a looped strap 3 arranged in a vertical plane and having 20 a forked outer end in the sides of which horizontal slots 4 are formed, these slots being longer than the width of the key 2 that passes therethrough, this key pulling upon the yoke when the gear is subject to pulling 25 strains and moving inwardly in the slots 4 when the gear is subject to buffing or pushing strains. The key 2 passes through horizontal slots 5 formed in the draft or center sills 6, the key occupying a middle position in 30 these slots when the draft gear is normal or idle and being moved outwardly in these slots when the gear is subject to pulling strain and inwardly in these slots when the gear is subject to pushing or buffing strain. Bridge pieces 7 and 9 underlie the draft or center sills and are in supporting relation to the coupler stem and yoke. The inner end of 35 the stem and the outer end of the yoke are supported by means of the key 2 and the bottom sides of the slots 5 on which this key slides. The yoke surrounds an outer follower 10 and an inner follower 11. The outward movement of the outer follower is limited by draft lugs 12 secured upon the inner faces of 40 the center sills and the inner movement of the inner follower is limited by draft lugs 13, similarly secured. When the gear is subject to pushing or buffing strains, the outer follower 10 is moved inwardly by the inner end of the coupler stem and the inner follower 11 is held from inward movement by the draft lugs 13, the inner end of the yoke being desirably interposed between the follower 11 and the draft lugs 13. When 45 the gear is subject to pulling strains, the inner follower 11 is moved outwardly by the rear end of the coupler yoke and the outer follower 10 is held against outward movement by the draft lugs 12. The movements of the followers longitudinally of the gear are resisted by the mechanism of my invention.

50 The motion retarding mechanism is inclusive of one group of friction plates 14 and a second group of friction plates 15, these

55 plates being movable transversely thereof and of the gear, both groups of plates being movable longitudinally of the plates and of the gear in response to pulling and pushing draft strains, respectively. The plates of each group are alternated with the plates of the other group and have frictional engagement therewith. A spreading device, subject to draft strains, is disposed in the midst of the plates of both groups and presses outwardly upon the plates on each side thereof in response to draft strains. This spreading device is desirably in the form of an inwardly tapering wedge portion 16 which constitutes the inner end portion of the center column 60 member 17 receiving end thrusts in both directions, which is, preferably, integrally formed with the outer follower 10. The spreading device is desirably also inclusive of washer plates 18 of uniform thickness, between which the wedge 16 is disposed, these washer plates being especially replaceable to compensate for wear. Said column member supports the elements 14, 15 and 18. The washer plates also function similarly to plates 14 and are included in the same group therewith. The plates 14 and 18 are formed with notches 19 and 20 in their bottom and top sides, these notches receiving the ribs 21 and 22 which are formed upon the inner faces of the horizontal flanges 23 and 24 of the center column structure. Said ribs are disposed transversely of these plates and the gear and serve to cause these plates to move with the center column and the follower 10 that is a part of the center column structure. The wedge 16 causes the washer plates 18 to converge inwardly. These washer plates cause the plates 15, contacting therewith, also to converge inwardly. The plates 15 cause the plates 14, next to and on the outer sides thereof, to converge inwardly. These plates 14 cause the plates 15, next to and on the outer sides thereof, to converge inwardly, and so on, the wedge 16 thus causing the plates on one side thereof to slope inwardly and similarly toward the axis of the gear and the plates on the other side thereof also to slope inwardly and similarly toward the axis of the gear. The plates 15 are engaged by the follower 11 and are moved outwardly thereby in response to pulling strains and are stationary when the draft gear is subject to pushing strains. As these plates 15 are slightly oblique with respect to the axis of the gear, they are pressed upon outwardly and laterally by the action of the spreading element 16 and the plates 14 and 18 that are similarly oblique to the axis of the gear.

60 As the two groups of plates are relatively moved longitudinally of the gear, frictional engagement between the plates of one group and the plates of the other group occurs, the friction producing pressure between the plates of the two groups obviously increas-

ing, due to friction between elements 27 and adjacent plates 14 as the draft strain increases. That is, the friction producing action of the spreading device 16, 18, is increased as the draft strain is increased and the gear is moved toward closed position and, practically, ceases as the draft strain is reduced, the construction being such that release of motion retarding frictional engagement between the plates of the two groups is quickly effected when the draft strain is reduced. Outward transverse movement of the plates on each side of the gear axis is resisted by the springs 25. These springs desirably also constitute application springs, being arranged to press inwardly upon the plates with increasing force as the draft strains increase. The friction between the plates of the two groups is thus not only increased in response to relative movement of the two groups due to increasing draft strains, but is also further increased by the increasing spring pressure of the springs 25 as the draft strains increase. In the preferred embodiment of the invention, the springs 25 are bottomed upon the follower 10 at their outer ends and engage a floating draft strain transmitting member 26 at their inner ends. The center column member 17 is interposed between the springs and the floating member 26 crosses the column member 17 and preferably surrounds the same, the wedging portion 16 projecting inwardly beyond the member 26. The springs 25 press upon the floating member 26 and the floating member 26 presses upon the inwardly tapering friction wedge blocks 27. These wedge blocks frictionally engage the friction wedge portions 28 that constitute outer continuations of the inner follower 11. The friction plates are desirably arranged in vertical planes as are also the wedging elements 27 and 28. The structure is strengthened by connecting the wedging elements 28 by means of the webs 29 which form with the wedging elements 28 and the follower 11, itself, an open ended box receiving the inner and the major portions of the plates and blocks. The elements 27 and 28, in conjunction with the springs 25, constitute a constricting device which laterally embraces the plates and functions to take part in effecting increasing frictional engagement between the parts as the draft strain increases, as explained. As the draft strain increases, the wedge blocks 27 will move apart, the springs 25 increasingly opposing this relative movement of these blocks. The relative movement of the two groups of friction plates longitudinally of the gear is desirably opposed by the center column member 17 and its wedging portion 16, the inner end of this wedging portion engaging the follower 11 when the limit of relative longitudinal movement of the two groups of plates has been reached in response

to draft strains, to withstand oversolid impact.

When the two groups of friction plates are relatively moved longitudinally of the gear in response to draft strains, the plates 15 are projected forwardly of the plates 14 and 18. In being thus projected, the plates 15 press upon a floating member, preferably the spanner 30 and the spanner presses upon the inner ends of the release springs 31 whose outer ends are bottomed upon the follower 10. These release springs are under a minimum degree of compression when the gear is released and then press, with minimum pressure, upon the spanner 30 and through the spanner upon the plates. The compression of the springs 31 is increased according to the extent to which the plates 15 are projected forwardly beyond the plates 14 and 18. When the draft strains are reduced, the release springs 31 function to restore the two groups of plates to their normal or idle relative positions in which the forward ends of the plates of both groups are substantially flush. The releasing power of the springs 31 is stored therein when the gear is being put under compression to be in readiness to act when the draft strain is reduced, this power increasing as the friction is increased in correspondence to increasing draft strain. The likelihood of the gear "sticking", on release, is thus effectively minimized, if not altogether overcome.

The application springs 25 are desirably nested in the release springs 31. The spanner 30 is desirably surrounded by the column member 17 and passes through an elongated opening 32 in this column member, the spanner being movable in this opening longitudinally of or with respect to said column member. The spanner is desirably bifurcated at its ends so as to have extended engagement with the inner ends of the release springs 31 between which the column member 17 is disposed and also with the forward ends of the plates 15.

Assembling bolts 33 pass through the ears 34 of the H shaped center column, the floating member 26 and the corner portions 35 of the wedge block actuator 11, 28. These bolts serve to hold the gear parts together before installation and after removal of the gear.

While the wedge block actuator 11, 28 is shown at the inner end of the gear and the follower portion 10 of the H shaped center column is shown at the front end of the gear, the invention is not to be thus limited, the spring and friction mechanism of the gear obviously operating similarly with draft strains applied at either end.

In the preferred embodiment of the invention, the notches 19 and 20 are not quite filled, lengthwise of the gear, by the ribs 21 and 22 on the center column, an arrange-

ment affording sufficient lost motion to permit the spring mechanism to initially take the impact without then producing friction. In releasing, the first movement of the gear 5 is the sliding movement, as a unit, of the friction plates 14, 15 and 18, the wedge blocks 27, the wedge block actuator 11, 28, and the floating members 26 and 30, this initial sliding release movement being very limited and 10 continuing until the lost motion permitted by the clearance between the ribs 21 and 22 and the notches 19 and 20 is absorbed. When this clearance is taken up and the friction plates 14 and 18 are brought in firm engagement with said ribs 21 and 22, there will be 15 a slight impact which will tend to start relative movement between the friction plates of the two groups. As the movement continues, the friction wedge blocks 27 will move toward 20 each other, due to the inclination of the friction plates to the gear axis, and the friction set up between these blocks 27 and the wedge elements 28 of the follower 11 will reduce the wedging pressure and facilitate release. The application springs 25, during the release movement, also overcomes the frictional resistance between wedge blocks 27 and the adjacent plates 14. This will reduce the force transmitted from the application 25 springs to the wedge blocks and thus decrease the wedging pressure on the friction plates during release. In case the force of the release springs is not sufficient to overcome the friction of plates 15 during release, the application springs will move the floating member 26, the wedge blocks 27, and the follower 11 inwardly until the floating member 26 comes in contact with the front ends of plates 15. Pressure on the wedge blocks is 30 consequently then relieved, both the application springs and release springs functioning to restore plates 15 to their normal relative positions.

I employ the term "center column" in the 45 sense that it is rigid and receives end thrusts in both directions due to draft strains.

Changes may be made without departing from the invention.

Having thus described my invention, I 50 claim:

1. A friction draft gear including a flanged central column having a tapered portion; intercalated friction plates supported by the flanged formation of the central column and bearing against said tapered portion of the column; means for setting up pressure on said plates; and means for returning the plates to release position.

2. A friction draft gear including a central 55 H-shaped column having a tapered portion and having its web portion arranged longitudinally of the gear; relatively longitudinally movable intercalated friction plates supported by column flanges on each 60 side of the column web and bearing against

said tapered portion; spring means on each side of the column; a transverse floating member cooperating with the relatively movable friction plates passing through and movable longitudinally of the gear within an opening formed through the web, said floating member receiving pressure of said 70 spring means, said column serving to take over-solid impact and limit the movement of the friction plates, and means for setting up 75 pressure on said plates.

3. A friction draft gear including a central column; two groups of relatively longitudinally movable intercalated friction plates mounted obliquely on both sides of the column and supported thereby; means for setting up pressure on the plates and yieldingly resisting relative motion of the plates; and means for returning the plates to release position.

4. A friction draft gear including a central column and having a wedge supported by the column; groups of relatively longitudinally movable intercalated friction plates supported by said column on each side 90 of the wedge; means for setting up pressure on the outside plates and yieldingly resisting relative motion of the plates; and means for returning the plates to release position.

5. A friction draft gear including a center 95 column; two groups of relatively longitudinally movable intercalated friction plates supported on the sides thereof; means for setting up pressure on the plates; release spring means; and a release member between 100 the release spring means and one group of plates and extending through the column and transmitting pressure from the spring means to the plates.

6. In a draft gear, a longitudinal central 105 column having a follower plate at one end adapted to receive spring means, said column being formed with an opening therethrough, adapted to receive a floating member in engagement with said spring means and subject to strains imposed upon the gear, the end of said column opposite to said follower bearing friction means co-operating with said floating member under compressive strains.

In witness whereof, I hereunto subscribe my name.

ALBERT F. STUEBING.
